W. J. BLIFFERT

INTAKE MANIFOLD

Filed Oct. 29, 1923

FIG. 1

FIG. 2

Inventor
WALTER J. BLIFFERT

By *Daniel F. Brennan*
Attorney

Patented Apr. 6, 1926.

UNITED STATES PATENT OFFICE.

WALTER J. BLIFFERT, OF MILWAUKEE, WISCONSIN.

INTAKE MANIFOLD.

Application filed October 29, 1923. Serial No. 671,556.

To all whom it may concern:

Be it known that I, WALTER J. BLIFFERT, a citizen of the United States, residing at Milwaukee, county of Milwaukee, and State 5 of Wisconsin, have invented a new and useful Improvement on an Intake Manifold, of which the following is a specification.

This invention relates broadly to internal combustion engines, and has particular reference to improvements in intake manifolds, more especially for the purpose of improving the function of such devices to the end that the flow of combustible mixture will be facilitated and the general efficiency of the 15 engine increased.

The principal objects and advantages which characterize this invention reside in the provision of an improved means for conducting a combustible mixture to an 20 internal combustion engine or to other apparatus for combustion; the provision of an improved means for conducting a combustible mixture to the cylinders of a conventional internal combustion engine having 25 more than one cylinder; the provision of improved means for conducting a combustible mixture to the cylinders of an internal combustion engine in a substantially continuous non-interrupted path; the provision 30 of improved means for delivering a combustible mixture in equal increments to the several cylinders of an internal combustion engine; the provision of improved means for conducting a combustible mixture 35 to the cylinders of an internal combustion engine in a path which is substantially uninterrupted and in which the turns or bends are described about arcs whereby to eliminate baffles or other walls which produce 40 condensation or retardance of the free flow of the mixture; the provision of improved means for conducting a combustible mixture to an internal combustion engine which affords a substantially continuous path for 45 flow of the mixture so that the flow of the mixture is in the same direction at all times, and is substantially uninterrupted, thereby improving the distribution of the mixture to the cylinders.

50 This invention is further characterized by the provision of an improved intake

manifold in which the flow of the combustible mixture is unidirectional, that is, does not reverse its direction of flow and therefore is prevented from backing up or condensing; the provision of an improved intake manifold for distributing equally a combustible mixture to the several cylinders of an internal combustion engine; the provision of an improved intake manifold characterized by the embodiment therein of intercommunicating passageways whereby the stream or streams of combustible mixture are counter-balanced and condensation is reduced to a negligible minimum and an even distribution of fuel to all of the cylinders is assured; and the improvement and simplification in general of devices of the character referred to.

This invention is still further characterized by the provision of an improved intake manifold for internal combustion engines wherein means is provided for causing the combustible mixture to follow an unidirectional and uninterrupted path through the manifold; the provision of an improved intake manifold having an arrangement of passageways for providing against lagging of the fuel behind the air and to afford means which tends to overcome the inertia of the stream of combustible mixture by maintaining the stream constantly in motion; the provision of an intake manifold characterized as above set forth wherein backing up of the stream of combustible mixture is practically entirely eliminated due to the continued motion of the stream through the manifold; the provision of an improved intake manifold which operates to supply a combustible mixture of uniform volatility and whereby to insure delivery of the same quantity and value of mixture to all the cylinders; and the provision of an improved intake manifold which operates to eliminate pulsations or other interruptions in the flow of the combustible mixture and thereby prevent the wave motion of the fuel and thus tend to stabilize the mixture and generally increase the efficiency of the engine.

The foregoing and such other objects and advantages as may appear or be pointed out as this description proceeds, are attained

in the structural embodiment illustrated in the accompanying drawings, in which:

Figure 1 is a front elevational view, partly in vertical section, of one form of my invention;

Figure 2 is a top plan, similarly partly in horizontal section.

The basic principle embodied in this invention is predicated on the proposition that in the conventional intake manifold the fuel mixture must first be lifted from the carburetor, that is, the inertia of the mixture must be overcome, and then the engine valve closes and the flow momentarily ceases, this condition prevailing even in engines having a large number of cylinders. The necessity, therefore, of first starting the flow of the mixture and then constantly repeating this operation results in pulsations and in lagging of the atomized fuel, fuel waves, wastes power and requires a greater lapse of time before the combustible mixture actually begins to enter the cylinder. The present invention eliminates these objections mainly by providing for the continuous flow of the combustible mixture, therefore eliminating reversal of the flow, and it follows that if the flow is substantially unidirectional it must be constant, and of a substantially constant mixture of air and fuel.

Referring now more particularly to the drawings, and first to Figures 1 and 2, wherein an intake manifold of this invention is illustrated for use on a four cylinder engine, I provide a structure, which is preferably integral and includes a body 1 having an inlet 1^a provided with a flange 2, whereby the manifold may be bolted or otherwise fixedly secured to any conventional form of carburetor, which, for obvious reasons, is not shown.

The body 1 is formed with the two diverging conduits or passageways 8 and 9 which communicate with the inlet 1^a, and terminate in spaced relationship. The conduits 8 and 9, of the manifold are provided with outlets 6 and 7 which are adapted to be connected, in the present instance, to the inlet ports of the cylinders. One each of the outlets 6 and 7 may be provided for each cylinder or one for each pair of cylinders.

The upper or discharge ends of the legs 8 and 9 are placed in direct communication by the provision of the auxiliary series of conduits including the passageways 12-13 and 14-15, these passageways intersecting at their medial portions to form a chamber 5. This communication of the passageways serves to balance the system and to eliminate any tendency of reversal by affording a substantially circular path which the fluid may take, say through passageways 8, 12, chamber 5 and passageway 15.

From an inspection of Figure 2, it will be observed that the passageways 12-13 and

14-15 are curved outwardly and are tapering from their outer ends toward the chamber 5. The purpose of this arrangement is to prevent these auxiliary conduits from interfering with the exhaust manifold (not shown) and in order to provide for acceleration of the flow of mixture and thus eliminate any tendency for a lagging of the fuel entrained in the air.

It will further be observed that the outlet openings 6 and 7 are of smaller diameter than that of the legs 8 and 9 of the manifold, so that one cylinder alone cannot "steal" the combustible mixture entirely at any one stroke from either of the legs 8 or 9.

In operation, depending upon which of the cylinders of the engine is on the intake stroke, the combustible mixture flows continuously through the legs 8 and 9 of the manifold, the flow in said legs always being in one direction as indicated by the arrows. However, the flow of the mixture in each of the auxiliary conduits is opposite because these conduits are in effect continuations of the main conduits or legs 8 and 9.

For instance when a cylinder connected to the outlet 6 is on the intake stroke, the cylinder connected to the outlet 7 is closed, and may be either on the compression or on the scavenging stroke, depending upon the timing. Assuming that the valve of the cylinder connected to outlet 6 is open and that cylinder is inducting the mixture the flow is in the direction of the arrows B and B¹, the flow from conduit 9 being as indicated in conduit 14-15 because of, first, the momentum of the mixture in leg 9, and because the area of the opening between conduit 15 and leg 8 is greater than that of conduit 12 and leg 8. When the outlet 6 is closed, the outlet 7 substantially simultaneously opens and flow in the conduit 12-13 and leg 9 is produced the same as the flow was produced in conduit 8, 14-15. While slight oscillation of the flow might occur in the passageways 12-13 and 14-15, this is only possible at the instant of the alternate opening and closing of the valves and is of negligible incident or effect in the operation. The flow of combustible mixture is therefore substantially constant and unidirectional.

It will, of course, be obvious that the number of legs 8 and 9, the size of same, and the number and size of the outlet openings of the manifold may be varied as found desirable, depending upon the type and size of the engine to which the manifold is to be secured for operation, and therefore I reserve the right to make minor alterations within the purview of the invention.

I claim:

1. In a device of the character described, an intake manifold having a plurality of

divergent ducts, and auxiliary ducts connecting said divergent ducts, said auxiliary ducts being interconnected and constricted intermediate their ends.

5 2. In a device of the character described, the combination with an internal combustion engine, having intake ports, passageways for connecting a carburetor with said ports, and auxiliary passageways connecting said ports, 10 said auxiliary passageways being interconnected at their medial portions.

3. In a device of the character described, in combination, an intake passageway having at least two branches, said branches having 15 outlets, and auxiliary passageways connecting said outlets, and said auxiliary passageways being in communication with each other between said outlets.

4. In a device of the character described, 20 the combination with an internal combustion engine, having intake ports, passageways for connecting a carburetor with said ports, and auxiliary passageways connecting

said ports, said auxiliary passageways being interconnected and reduced in size at their 25 medial portions.

5. In a device of the character described, in combination, an intake passageway having at least two branches, said branches having outlets, and auxiliary passageways connecting said outlets and of smaller size than 30 said branches, said outlets being of smaller size than said branches for preventing stealing of the mixture from any of the branches.

6. In a device of the character described, 35 in combination with an internal combustion engine, an intake manifold having a plurality of divergent ducts provided with outlets directly to the engine cylinders, an auxiliary duct connecting said divergent ducts 40 ahead of said outlets, and a further auxiliary duct connecting said divergent ducts at said outlets.

In testimony whereof I affix my signature at 207 Wells Street, Milwaukee, Wisconsin.

WALTER J. BLIFFERT.
